[57] CLAIM

The ornamental design for a portfolio, as shown and
described.

DESCRIPTION

FIG. 1 is a perspective view of a portfolio showing my
new design, viewing the front panel;
FIG. 2 is a front elevational view thereof;
FIG. 3 is a top plan view thereof;
FIG. 4 is a bottom plan view thereof;
FIG. 5 is a left end elevational view thereof; and
FIG. 6 is a rear elevational view of the portfolio with
the handles in lowered positions.
The characteristic feature of the design resides in the
inset and recessed side pockets, with stitching closely
paralleling both sides of the margin of the recess.
